ROTARY SPEED RESPONSIVE APPARATUS

Lewis E. Thatcher, Chicago, Ill., assignor to Gaylord Products, Incorporated, Chicago, Ill., a corporation of Delaware

Application May 2, 1955, Serial No. 505,410

8 Claims. (Cl. 200—80)

This invention relates to improvements in a device for actuating an electric switch in response to the rate of rotation of a rotating body, and refers particularly to a device of the character described which is effective in operation, simple in construction and is operable when the rotating body rotates in either direction.

In copending application for United States Patent Serial No. 505,478 filed May 2, 1955, in the name of Lewis E. Thatcher, a device is shown and described for actuating or initiating a predetermined operation or producing a predetermined signal by transforming rotation of a plurality of associated rotating plates, to a lateral or radial movement of one of said plates to actuate an electric switch in response to a predetermined rate of rotation of said plates.

The present invention employs the basic concept set forth in said copending application and contemplates relatively simple, effective apparatus for accomplishing the end result intended.

The features, objects and advantages of the present invention will be apparent from the accompanying drawing and following detailed description.

In the drawing,

Fig. 1 is a longitudinal sectional elevation illustrating a device embodying the concepts of the present invention.

Fig. 2 is a transverse sectional view taken on line 2—2 of Fig. 1, showing the switch in closed position.

Fig. 3 is a view similar to Fig. 2 showing the switch in open position.

Referring in detail to the drawing, 1 indicates a cup-shaped housing having a bottom 2 and lateral wall 3. A closure disc 4 is adapted to be positioned upon the upper edge of the wall 3 and is secured thereto by cement 5 or the like thereby providing a closed compartment 6. A boss 7 is preferably formed integral with the bottom 2 and extends downwardly therefrom. A similar boss 8 is formed integral with the closure disc 4 and extends upwardly therefrom. A shaft 9 is journaled for rotation in the bosses 7 and 8, said shaft passing through the central portion of compartment 6.

The shaft 9 is adapted to be rotated by external means (not shown) which may be coupled to said shaft. If the device 1 is used in conjunction with an automotive vehicle, for instance, the shaft 9 may be coupled to the speedometer cable of the vehicle and consequently will rotate in timed relationship with said speedometer cable which, in turn, will rotate at a speed proportional to the movement of the vehicle. If a speedometer cable is coupled to the shaft 9 the cable sheath may carry a female coupling (not shown) which may be engageable with threads 10 formed upon the outer surfaces of the bosses 7 and 8.

Although the present device is particularly adaptable for use on automotive vehicles to control an anticerlip device which may be carried by the vehicle or to control a speed governor, it is to be understood that the present invention is not to be specifically limited to this environment since it will find use in many other applications.

Within the compartment 6 an upper driving member 11

may be mounted upon shaft 9, the driving member 11 comprising a hub portion 12 and an outwardly extending annular flange 13. A lower driving member 14 may also be positioned within the compartment 6 and may also be mounted upon shaft 9, said lower driving member comprising hub portion 15 and an outwardly extending annular flange portion 16. A key 17 may function to rigidly secure the driving members 11 and 14 to shaft 9 whereby said driving members are rotated when shaft 9 is rotated.

10 A driven member 18 loosely embraces the hub portions 12 and 15 of the driving members 11 and 14, said driven member being provided with a central aperture 19 which is sufficiently large to permit appreciable radial eccentric movement of the driven member with respect to shaft 9 and with respect to the driving members. The driven member 18, at its outer periphery, is provided with a rim 20 which lies outwardly from the outer peripheries of the flange portions 13 and 16 of the driving members 11 and 14 respectively.

15 The outer faces of the driven member 18 and the opposed faces of the flanges 13 and 16 are spaced from each other and a plastic material 21 is positioned in said spaces, said plastic material being in contact with the inner surfaces of the flanges 13 and 16 and also in contact with the body portion of the driven member 18. The plastic material 21 comprises a material preferably having appreciable viscosity and shear strength whereby when the driving members are rotated the driven member tends to rotate through the agency of the material 21.

20 The outer rim 20 of the driven member 18 is provided with a slot 22, the edges defining the slot being substantially tapered. A radial projection 23 is carried by the flange 13 and is preferably formed integral with said flange, said radial extension 23 being adapted to be positioned in the slot 22 provided in the rim 20. The arrangement is such that when the driving members rotate, the driven member is positively rotated by the interengagement of the projection 23 in the slot 22 and also by the frictional resistance of the material 21 interposed between the driving members and the driven member. The arrangement is also such that the driven member 18 may move radially with respect to the driving members 11 and 14 whereby said driven member may move to either an eccentric or a concentric position relative to said driving members. The radial movement hereinbefore described is permitted by virtue of the fact that the projection 23 is slidably positioned within the slot 22. Of course, radial or eccentric movement of the driven member 18 with respect to the driving members 11 and 14 is resisted by the viscosity and shear strength of the material 21.

25 The material 21 preferably comprises a silicone oil, grease or paste or may comprise relatively heavy industrial grease. However, the silicone material is preferred because of its physical characteristics. For instance, its viscosity and shear strength remain substantially constant regardless of the rate of shear. In addition, the viscosity and shear strength of such silicones is substantially unaffected by temperatures throughout a relatively wide range. Consequently, the frictional resistance between the driving members and the driven member remains substantially constant over a relatively wide range of operating conditions.

30 A portion of the lateral wall 3 of the housing 1 is extended outwardly to form a switch compartment 24 in which a conventional snap switch 25 is positioned. The snap switch 25 comprises a frame plate 26 which carries a supporting flange 27, the frame plate 26 being mounted upon the inner face of wall 28 defining a portion of the compartment 24. A resilient switch arm 29 is pivotally carried upon the flange 27 and at its end carries a contact point 30 which is juxtaposed with respect to a stationary contact point 31 carried upon and insulated from

frame 26. Contact point 31 is connected to an electrical conductor 32 which, at its opposite end, may be connected to a suitable control circuit (not shown). A second conductor 33 connects with and grounds frame 26. The conductor 33 also connects with the same circuit to which the conductor 32 is connected. When the switch arm 29 is positioned, as shown in Fig. 2, contact points 30 and 31 are closed and hence the circuit to which conductors 32 and 33 are connected is energized. When the switch arm 29 is in the position shown in Fig. 3, the contact points 30 and 31 are separated and the external circuit is deenergized. A pressure bar 34 is pivotally mounted upon the flange 27 and is acted upon by the lower end of the resilient switch arm 29. The resiliency of the arm 29 exerts a resilient force upon the pressure arm 34 tending to rock said pressure arm in a counterclockwise direction, as viewed in Figs. 2 and 3.

At the outer end of the pressure arm 34 an abutment plate 35 is carried, said plate being pivotally secured, as at 36, to the end of pressure arm 34. The abutment plate 35 comprises a pair of oppositely extending arms 37 and 38, arm 37 having an arcuate contact finger 39 and arm 38 having an arcuate contact finger 40. By virtue of the resilient force acting upon the pressure arm 34 the plate 35 is urged toward the outer periphery or rim 20 of the driven member and the finger portions 39 and 40 make resilient pressure contact with the periphery of rim 20. Accordingly, the resilient pressure exerted upon arm 34, through the fingers 39 and 40, tends to urge the driven member 18 to an eccentric position with respect to the driving members 11 and 14.

As has been described in the application for patent, hereinbefore identified, two opposing forces are in operation, the force of arm 34 being applied by the fingers 39 and 40 radially to the driven member 18, which will be hereinafter referred to as the "active force," and the force of friction between the driving and driven members, which will hereinafter be referred to as the "reactive force." The active force tends to move the driven member 18 to an eccentric position relative to the driving members 11 and 14 and this force is opposed by the reactive force. When the shaft 9 is stationary the reactive force comprises essentially the viscous resistance and shear resistance of the material 21. When the shaft 9 rotates, the reactive force is also a function of the rate of rotation.

When the shaft 9 is stationary, the active force overbalances the reactive force and the driven member 18 will be moved radially to an eccentric position. If shaft 9 is then rotated, the reactive force is augmented and, depending upon the constants employed, which will be hereinafter more fully discussed, a rate of rotation will be reached where the active and reactive forces become equal. It will be noted that the driven member 18 is positively rotated by the interengagement of the projection 23 in slot 22. Hence, if the driven member is initially eccentric below the critical balancing speed, mentioned hereinbefore, the driven member will remain eccentric in a direction away from the active force. However, as the rate of rotation increases the degree of eccentricity will decrease until at said critical speed the driven member 18 will move to substantial concentricity with the driving members. When this condition is reached, arm 34 will have been moved to the point where switch 25 is actuated to closed position.

If the rate of rotation is sufficiently high the active force will be unable to radially shift the driven member from its eccentric position if it were initially eccentric and, hence, the driven member would remain eccentric to the driving members but the eccentricity would continuously change relative to the active force, that is, driven member 18 will continuously rotate eccentrically with respect to the driving members.

To avoid this action, a stop 41 is mounted upon base 2 in the path of travel of plate 35 whereby eccentricity

of the driven member toward the active force is inhibited. Accordingly, when the rotation of shaft 9 exceeds the critical speed, the driven member having been moved to concentric position at the critical speed, will remain at concentric position. Hence, switch 25 will be actuated to closed position at said critical speed and will remain closed at all speeds thereafter.

When shaft 9 slows down to a speed below the critical speed, the active force will predominate and, hence, the driven member will be moved to an eccentric position away from said active force and switch 25 will be actuated to open position.

To construct a device which will act at a predetermined critical speed, the following factors must be observed: The strength of spring 29; the physical characteristics of the material 21 as to viscosity and shear strength; the thickness of the layers of material 21, and the areas of the driving and driven members wetted by the material 21. Of course, the greater the strength of spring 29 the greater will be the active force. With a material of relatively high viscosity and high shear strength a relatively high reactive force may be obtained and vice versa. The reactive force would also be inversely proportional to the thickness of the layers of material and would be directly proportional to the wetted areas of the driving and driven members. Thus, devices may be constructed responsive to predetermined rates of rotation over relatively wide ranges of rates of rotation.

In the present invention it will be noted that although the driven member is radially movable a limited degree with respect to the driving members 11 and 14, the driven member is ultimately positively driven rotationally by the driving member 13. Thus rotation of the driven member 18 does not depend upon the material 21.

In addition, by virtue of the physical construction of plate 35, the device is operative to perform its intended function regardless of the direction of rotation thereof.

It will be apparent to any one skilled in the art that many modifications may be made in the present invention without departing from the spirit thereof, and, hence, it is not intended that the invention be limited to the precise structure shown and described except as necessitated by the appended claims.

I claim as my invention:

1. A device for actuating an electric switch in response to the rate of rotation of a rotating body which comprises, a driving plate rotatable about an axis transverse to its face, a driven plate embracing said axis and eccentrically movable with respect to said axis and disposed in substantially plane-parallel relationship to said driving plate, a radial projection carried by said driving plate slidably engageable in a slot provided in the periphery of said driven plate whereby said driven plate rotates with said driving plate but may move eccentrically with respect to said driving plate, an electric switch, a spring-pressed actuating arm for said switch, a contact plate carried by said actuating arm and resiliently contacting the periphery of said driven plate to urge resiliently said driven plate to an eccentric position with respect to the driving plate when said plates are stationary, means for frictionally engaging the opposed surfaces of the driven plate and driving plate, and means for rotating said driving plate to urge said driven plate toward concentric position with respect to said driving plate and actuate said switch against the resilient force of said actuating arm.

2. A device for actuating an electric switch in response to the rate of rotation of a rotating body which comprises, a driving plate rotatable about an axis transverse to its face, a driven plate embracing said axis and eccentrically movable with respect to said axis and disposed in substantially plane-parallel relationship to said driving plate, a radial projection carried by said driving plate slidably and rockably engageable in a slot provided in the periphery of said driven plate whereby said driven plate rotates with said driving plate but may move eccentrically with

respect to said driving plate in a plane parallel to the plane of said driving plate, an electric switch, a spring-pressed actuating arm for said switch, a contact plate carried by said actuating arm and resiliently contacting the periphery of said driven plate to urge resiliently said driven plate to an eccentric position with respect to the driving plate when said plates are stationary, means for frictionally engaging the opposed surfaces of the driven plate and driving plate, and means for rotating said driving plate to urge said driven plate toward concentric position with respect to said driving plate and actuate said switch against the resilient force of said actuating arm.

3. A device for actuating an electric switch in response to the rate of rotation of a rotating body which comprises, a driving plate rotatable about an axis transverse to its face, a driven plate embracing said axis and eccentrically movable with respect to said axis and disposed in substantially plane-parallel relationship to said driving plate, a radial projection carried by said driving plate slidably engageable in a slot provided in the periphery of said driven plate whereby said driven plate rotates with said driving plate but may move eccentrically with respect to said driving plate, an electric switch, a spring-pressed actuating arm for said switch, a substantially U-shaped contact plate pivotally carried by said actuating arm, the arms of said contact plate resiliently contacting the periphery of said driven plate to urge resiliently said driven plate to an eccentric position with respect to the driving plate when said plates are stationary, means for frictionally engaging the opposed surfaces of the driven plate and driving plate, and means for rotating said driving plate to urge said driven plate toward concentric position with respect to said driving plate and actuate said switch against the resilient force of said actuating arm.

4. A device for actuating an electric switch in response to the rate of rotation of a rotating body which comprises, a driving plate rotatable about an axis transverse to its face, a driven plate embracing said axis and eccentrically movable with respect to said axis and disposed in substantially plane-parallel relationship to said driving plate, a radial projection carried by said driving plate slidably engageable in a slot provided in the periphery of said driven plate whereby said driven plate rotates with said driving plate but may move eccentrically with respect to said driving plate, an electric switch, a spring-pressed actuating arm for said switch, a substantially U-shaped contact plate pivotally carried by said actuating arm, the arms of said contact plate resiliently contacting the periphery of said driven plate to urge resiliently said driven plate to an eccentric position with respect to the driving plate when said plates are stationary, relatively viscous plastic means for frictionally engaging the opposed surfaces of the driven plate and driving plate, and means for rotating said driving plate to urge said driven plate toward concentric position with respect to said driving plate and actuate said switch against the resilient force of said actuating arm.

5. A device for actuating an electric switch in response to the rate of rotation of a rotating body which comprises, a driving plate rotatable about an axis transverse to its face, a driven plate embracing said axis and eccentrically movable with respect to said axis and disposed in substantially plane-parallel relationship to said driving plate, a radial projection carried by said driving plate slidably engageable in a slot provided in the periphery of said driven plate whereby said driven plate rotates with said driving plate but may move eccentrically with respect to said driving plate, an electric switch, a spring-pressed actuating arm for said switch, a substantially U-shaped contact plate pivotally carried by said actuating arm, the arms of said contact plate resiliently contacting the periphery of said driven plate to urge resiliently said driven plate to an eccentric position with respect to the driving plate when said plates are stationary, a relatively viscous plastic silicone for frictionally engaging the opposed sur-

faces of the driven plate and driving plate, and means for rotating said driving plate to urge said driven plate toward concentric position with respect to said driving plate and actuate said switch against the resilient force of said actuating arm.

6. A device for actuating an electric switch in response to the rate of rotation of a rotating body which comprises, a substantially circular driving plate rotatable about an axis transverse to its face, a substantially circular driven plate embracing said axis and eccentrically movable with respect to said axis and disposed in substantially plane-parallel relationship to said driving plate, a circular rim carried by the outer periphery of said driven plate, a radial projection carried by said driving plate slidably engageable in a slot provided in the rim of said driven plate whereby said driven plate rotates with said driving plate but may move eccentrically with respect to said driving plate, an electric switch, a spring-pressed actuating arm for said switch, a contact plate carried by said actuating arm and resiliently contacting the rim of said driven plate to urge resiliently said driven plate to an eccentric position with respect to the driving plate when said plates are stationary, means for frictionally engaging the opposed surfaces of the driven plate and driving plate, and means for rotating said driving plate to urge said driven plate toward concentric position with respect to said driving plate and actuate said switch against the resilient force of said actuating arm.

7. A device for actuating an electric switch in response to the rate of rotation of a rotating body which comprises, a pair of spaced driving plates rotatable about an axis transverse to their faces, a driven plate embracing said axis and eccentrically movable with respect to said axis and disposed in substantially plane-parallel relationship to said driving plates, a radial projection carried by one of said driving plates slidably engageable in a slot provided in the periphery of said driven plate whereby said driven plate rotates with said driving plates but may move eccentrically with respect to said driving plates, an electric switch, a spring-pressed actuating arm for said switch, a contact plate carried by said actuating arm and resiliently contacting the periphery of said driven plate to urge resiliently said driven plate to an eccentric position with respect to the driving plates when said plates are stationary, means for frictionally engaging the opposed surfaces of the driven plate and driving plates, and means for rotating said driving plates to urge said driven plate toward concentric position with respect to said driving plates and actuate said switch against the resilient force of said actuating arm.

8. A device for actuating an electric switch in response to the rate of rotation of a rotating body which comprises, a driving plate rotatable about an axis transverse to its face, a driven plate embracing said axis and eccentrically movable with respect to said axis and disposed in substantially plane-parallel relationship to said driving plate, a radial projection carried by said driving plate slidably engageable in a slot provided in the periphery of said driven plate whereby said driven plate rotates with said driving plate but may move eccentrically with respect to said driving plate, an electric switch, a spring-pressed actuating arm for said switch, a contact plate carried by said actuating arm and resiliently contacting the periphery of said driven plate to urge resiliently said driven plate to an eccentric position with respect to the driving plate when said plates are stationary, means for frictionally engaging the opposed surfaces of the driven plate and driving plate, means for rotating said driving plate to urge said driven plate toward concentric position with respect to said driving plate and actuate said switch against the resilient force of said actuating arm, and stop means for abutting said actuating arm to prevent eccentric movement of said driven plate toward said actuating arm.
